COIN CONTROL AND SELECTING
MECHANISM

Kenly C. Bugg, Farmington, Mo., assignor to
Ozark Novelty Company, Farmington, Mo., a
corporation of Missouri

Refiled for abandoned application Serial No.
610,613, May 11, 1932. This application March
20, 1935, Serial No. 12,004

11 Claims. (Cl. 194—103)

This invention relates to coin control and selecting mechanism, and has special reference to mechanism for selecting and separating slugs and the like from the coins that are inserted in coin control machines or vending machines, in order to prevent fraudulent operation of the machines by use of slugs and the like.

It is known that attempts are frequently made to defraud vending machines by use of slugs of about the same size as the coins that are required to operate the machines. This fraudulent use of slugs for these dishonest purposes has grown enormously, so that it is necessary to make provision to prevent operation of the machines and other devices by use of the slugs.

An object of the invention is to provide a mechanism and devices whereby the spurious and fraudulent slugs and the like are separated and discharged away from the coins of proper value and thrown out of the way, so that they will not operate nor control the machines nor interfere with the proper operation of the machines when coins of proper value are inserted.

Various other objects of the invention, and its ready adaptability to many uses, will appear from the following description, reference being made to the accompanying drawings, in which—

Fig. 1 is a side elevation of the device showing the inlet opening through which the coins are inserted and the receptacle to which the fraudulent slugs and the like are discharged.

Fig. 2 is a view showing the selecting and separating mechanism whereby the coins and slugs are separated from each other, the parts being shown in their normal positions.

Fig. 3 is a similar view showing the devices in the positions to which they are operated by a slug differing in weight from the weight of the proper coin.

Fig. 4 is a view similar to Fig. 3 showing the devices in the positions to which they are operated by a coin of proper value.

Fig. 5 is a cross sectional view approximately on the line 5—5 of Fig. 2.

Fig. 6 is a view showing a variation of the invention for separating slugs of weights differing from each other and from the weight of the coins and discharging these slugs out of the machine, the parts being shown in their unoperated positions.

Fig. 7 is a view of the same mechanism in the position to which it is operated by a coin.

Fig. 8 is a view of the same mechanism in the position to which it is operated by a slug having a weight heavier than that of the coin.

Fig. 9 is a vertical sectional view on the line 9—9 of Fig. 8.

Fig. 10 is a sectional view on the line 10—10 of Fig. 8.

Fig. 11 is a view showing another variation of the invention for separating slugs of various weights from the coins, the parts being in their unoperated positions.

Fig. 12 is a view showing the parts in their operated positions.

Fig. 13 is a cross sectional view on the line 13—13 of Fig. 11.

The invention, as shown in Figs. 1 to 5, inclusive, comprises a front plate 1 provided with an opening 2 through which the coins are inserted. Spaced brackets 3 and 4 are attached to the inner side of the plate 1. An angular plate has one corner mounted on a pivot 5 supported by the plate 1 and the bracket 3, and has a corner 6 extending laterally toward the corner 7 of another angular plate that has a corner mounted on a pivot 8 supported by the plate 1 and the bracket 4.

The corners 6 and 7 of these angular plates extend toward each other and are necessarily engaged by a coin or slug passed through the hole 2 and dropped into the device.

A weight 9 is attached to the lower corner of the plate that swings from the pivot 5 and supports an arm 10 extending obliquely downwardly therefrom and terminating below a weight 11 attached to the lower corner of the plate that swings from the pivot 8.

The lower end of the arm 10 has a portion 12 that is bent and extended laterally toward the plate 1 in position to be engaged by a coin or slug dropping from the corners 6 and 7 of the pivoted plates.

The upper corner of the plate that is suspended from the pivot 8 has an arm 13 inclining upwardly in the general direction of the upper side of the opening 2, so that any coin or slug dropped through the opening 2 will be required to drop centrally upon the corner portions 6 and 7 of the swinging plates, as indicated by the coin 14 in Fig. 2 of the drawings.

A chute 15 is provided to receive the coins and a separate chute 16 is provided to receive the slugs. The chute 16 opens into a tray 17 into which the slugs drop.

A plate 18 is attached to and spaced from the plate 1 and cooperates therewith to guide the coins and slugs downwardly toward their respective chutes. The adjacent faces of the plates 1 and 18 are formed with ribs 19 and 20 against which the coins and slugs operate and which pre-

vent the adhesion to said plates of any substantial amount of dirt or other foreign substances.

The device just described is designed and adapted to operate and function to separate coins and slugs that have different weights. As stated, the coins are discharged into the chute 15 and the slugs into the chute 16 when the slugs are of less weight than the coins, although the coins may as well be discharged into the chute 16 and the slugs into the chute 15 should it be desired to use the device for separating slugs that are heavier than the coins.

In operation, when any coin of the proper value is dropped through the opening 2, said coin is required to move laterally and downwardly to the position of the coin 14 (Fig. 2). The momentum and weight of the coin operate the angular plates, thereby swinging the arm 10 downwardly and laterally to position in which the extension 12 on the end of said arm is vertically below the coin. The coin dropping onto the extension 12 is deflected laterally and caused to drop into the chute 15, as shown in Fig. 4.

When a slug 21 of less weight than a coin 14 is dropped through the opening 2, said slug drops onto the corners 6 and 7 of the angular plates and operates said plates. Being of less weight and moving at a slower speed than the coin, the slug does not swing the arm 10 laterally as far as said arm is swung by the heavier coin. On the contrary, the speed of downward movement of the slug is retarded and the arm 10 swings back far enough towards its starting position to place the extension 12 in position below the dropped slug, so that said arm will be struck with a slug and will deflect the slug laterally into the chute 16.

Thus the extent of movement of the arm 10 is determined by the weight and speed of movement of the slugs and coins. It being assumed that the slugs are of less weight than the coins, it follows as a necessary consequence that the arm 10 is moved to a less extent by the lighter slugs than it is moved by the heavier coins. Thus, the device constitutes a weighing instrument, whereby the coins of an approximate definite weight are separated from slugs of a different weight and the slugs are discharged through the outlet chute 16.

The invention shown in Figs. 6 to 10, inclusive, of the drawings possesses precisely the same construction and mode of operation as that above described with the exception that the arm 10 is displaced and an arm 22 of a different construction is substituted therefor. The remaining parts being the same as that already described, it is unnecessary to repeat the description thereof and it is only necessary to describe the construction, arrangement and mode of operation of the arm 22.

The arm 22 is bent to provide a lateral extension 23 that extends through a slot 24 in the back plate 18. This extension 23 is below the weight 11 and takes the place of the lateral extension 12 of the arm 10. Beyond the lateral extension 23 of the arm 22, there is an angular portion 25 of said arm having a lateral extension 26 extending toward the plate 1.

When the coin 14 (Fig. 7) is passed through the opening 2 and drops from the corners 6 and 7 of the swinging plates, said coin strikes the lateral extension 23 and is thereby deflected laterally. Dropping further, the coin 14 strikes the lateral extension 26 and is thereby deflected into the coin chute 15.

When the slug 21 of less weight than the coin 14 drops from the corners 6 and 7 of the pivoted angular plates, said slug strikes the lateral extension 23 of the arm 22, but being of less weight than the coin 14, this slug 21 does not move the arm 22 as far as said arm 22 is moved by the heavier coin. The slug 21, dropping from the extension 23, strikes the extension 26 and is thereby deflected laterally and caused to drop into the chute 16. It is clear that this device can be used with equal satisfaction and success to deflect the coins into the chute 16 and to deflect heavier slugs into the chute 15.

The invention, as shown in the remaining drawings, comprises two sets of selecting and separating devices of duplicate construction and both of which sets of selecting and separating devices are the same as the set of selecting and separating devices shown in Figs. 1 to 5, inclusive. These sets of selecting and separating devices are arranged one above the other and the upper set, being of the same construction and arrangement and being located in approximately the same position as the set of selecting and separating devices shown in Figs. 1 to 5, inclusive, the same reference characters are applied to this upper set of selecting and separating devices as are applied to corresponding parts in Figs. 1 to 5.

The lower set of selecting and separating devices is of the same construction and embodies the same parts as the upper set. Accordingly, the same reference characters with the exponent "a" are applied to the parts of the lower set as are applied to corresponding parts of the upper set.

When any coin 14a of the proper value is passed through the opening 2, said coin is required to move laterally and downwardly onto the corners 6 and 7 of the swinging plates of the upper set. The momentum and weight of the coin operate the angular plates, thereby swinging the arm 10 downwardly and laterally to position in which the extension 12 on the end of said arm is vertically below the coin. The coin being of proper weight and dropping onto the extension 12 is deflected laterally to the right of said extension 12 and drops onto the corners 6a and 7a of the lower set of angular plates. The momentum and weight of the coin operate these plates of the lower set, thereby swinging the arm 10a downwardly and laterally to position in which the extension 12a on the end of said arm is below the coin. The coin dropping onto the extension 12a is deflected laterally and caused to drop into the chute 15a. This is so because the momentum and weight of the coin are not sufficient to swing the arm 10a far enough to the left (Fig. 12) to deflect the coin to the right into the chute 16a.

When a slug heavier than the coin 14a is dropped through the opening 2, said slug engages the corners 6 and 7 of the upper set and swings the arm 10 laterally, causing said heavier slug to drop to the corners 6a and 7a of the lower set. This slug, being heavier than the coin 14a, swings the arm 10a laterally to a greater extent than said arm is swung laterally by the coin 14a. The momentum and weight of the slug being greater than the momentum and weight of the coin 14a, said slug is deflected laterally toward the right by the extension 12a, causing said slug to drop into the chute 16a.

When a slug 21a of less weight than the coin 14a is dropped through the opening 2, said slug drops onto the corners 6 and 7 of the upper set and operates the angular plates. The slug 21a

5 drops from the angular plates against the extension 12. The slug 21^a, being of less weight than the coin 14^a, does not swing the arm 10 laterally to the left as far as said arm is moved by the heavier coin. Accordingly, the slug 21^a drops onto the extension 12 in a manner to cause said extension 12 to deflect the slug 21^a toward the left and onto an abutment 27. The slug 21^a rolls along the abutment 27 and drops therefrom 10 into a chute 28 that is separate from the chutes 15^a and 16^a.

10 Accordingly, the invention shown in Figs. 11 and 12 will separate from the coins all slugs irrespective of whether the slugs are of greater or 15 less weight than the coins.

By actual operation, this invention has been found to obtain all of its intended objects and purposes in a highly efficient manner. The construction and arrangement of the parts comprising the invention may be varied otherwise than as specifically disclosed without departure from the nature and principle of the invention. I contemplate such variations as may be required to adapt the invention for its intended uses and, 20 without restricting myself in any unessential particulars, what I claim and desire to secure by Letters Patent is:—

1. Mechanism of the character described comprising pivotally supported devices for receiving and discharging between them coins and slugs to be separated from each other, and a deflector supported and operated by one of said devices and movable thereby to different positions according to the weight of the coins and slugs and 30 to deflect the coins in one direction and the slugs of different weight from the coins in another direction.

2. Mechanism of the character described comprising pivotally supporting weighing devices for receiving and discharging between them coins of predetermined value and weight and slugs of different weight from the coins, said weighing devices being operated by said coins and slugs, and a deflector supported and operated by one of said 40 weighing devices and extending into the path of movement of said coins and slugs to different positions according to the weight and momentum of the coins and slugs and deflecting the coins to one side thereof and the slugs of different weight 45 than the coins to the other side thereof.

3. Mechanism of the character described comprising a pivotally supported device adapted to be engaged and operated by coins and slugs and to discharge the coins and slugs to one side thereof, and a deflector member supported and operated by said device and moved to different positions according to the weight of the coins and slugs and adapted to be engaged in its operated positions by the coins and slugs and to 55 deflect the coins to one side thereof and the slugs to the other side thereof.

4. Mechanism of the character described comprising a pair of spaced plates, one of which has a hole for the insertion of coins and slugs, pivotally supported weighing devices between said plates adapted to be engaged and operated by coins and slugs inserted and dropped through said hole, a deflector member supported and operated by one of said devices to an extent corresponding to the extent to which said device is 60 operated by coins and slugs, and a part sup-

ported by said deflector member in position to be engaged by the coins and slugs dropping from said weighing devices and to deflect coins to one side thereof and the slugs of different weight from the coins to the other side thereof.

5. Mechanism of the character described comprising a pivotally supported member adapted to be engaged and operated by coins and slugs and moved thereby to permit the coins and slugs to drop therefrom, and a deflector supported 10 and operated by said member and engaged by the coins and slugs dropping therefrom and separating the coins from slugs differing in weight from the coins.

6. Mechanism of the character described comprising a pivotally supported member adapted to be engaged and operated by dropping coins and slugs, and a device supported and operated by said member in position to be engaged by the coins dropping from said member and to deflect 20 and separate coins from slugs having a weight different from the weight of the coins.

7. Mechanism of the character described comprising a pair of spaced pivotally supported members adapted to be engaged and operated by 25 coins and slugs dropped thereon and to discharge the coins and slugs downwardly between and from said members, and an element supported and operated by one of said members to position to be engaged by the coins and slugs dropping from 30 said members and to deflect the coins in one direction and the slugs of a different weight from the coins in another direction.

8. Mechanism of the character described comprising a pair of pivotally supported members 35 adapted to be engaged and operated by dropped coins and slugs and to discharge the coins and slugs downwardly between and from said members, an arm supported and operated by one of said members, and an extension on said arm 40 adapted to be engaged by the coins and slugs dropping from said members and to discharge the coins to one side thereof and the slugs of a different weight from the coins to the other side thereof.

9. Mechanism of the character described comprising pivotally supported members adapted to be engaged and operated by dropped coins and slugs, a device supported and operated by one of said members for deflecting in one direction slugs 50 of less weight than the coins and remaining slugs, and mechanism for separating the coins from heavier slugs.

10. Mechanism of the character described comprising pivotally supported devices adapted to be 55 engaged and operated by dropped coins and slugs, and a member supported and operated by one of said devices for separating into separate groups the coins and the slugs having different weights.

11. Mechanism of the character described comprising pivotally supported members adapted to be engaged and operated by dropped coins and slugs, a device supported and operated by one of said members for separating from the coins and the remaining slugs those slugs which differ in 65 weight from said coins and said remaining slugs, and mechanism adapted to be engaged and operated by said coins and said remaining slugs and separate said coins from said slugs.
